3 Claims. (Cl. 250—41.9)

This invention relates to mass spectrometry and particularly to means for suppressing spurious signals resultant from unwanted background ionization.

A mass spectrometer is an instrument for ionizing molecules of a sample to be analyzed and selectively sorting and measuring these ions as a function of their mass-to-charge ratio (specific mass). Mass spectrometers take many forms but universally include means for ionizing a sample, means for subjecting ions to forces tending to separate them as a function of their specific mass and means for selectively sensing ions of different specific mass. One form of mass spectrometer will be described in some detail herein.

In any mass spectrometer, ions other than those of interest are inevitably formed from metal surfaces, residual molecules, etc. and are referred to as background ions. Background ions exhibit completely unordered energy and by reason of this fact we have discovered means for selectively repressing the ion current produced by these background ions.

We have developed a method of mass spectrometry which minimizes the consequence of background ions. This method involves introduction into the ionizing region of a mass spectrometer of a molecular sample beam of ordered energy, ionizing molecules of the molecular beam, subjecting the ions to a propelling potential having a transverse component of potential to counteract the effect of the ordered energy of the ions produced from the sample and to focus the sample ions at an outlet from the region while simultaneously defocusing background ions of unordered energy.

We have further devised a means for selectively sampling molecules which enter an ion source with ordered energy in the presence of background molecules of unordered energy. The invention is useful in suppression of background in crucible-type ion sources or in ion sources using orifice-type inlet systems. The apparatus comprises an ion source enclosing an ionizing region, an apertured electrode, means for directing a molecular beam of material to be ionized into the region between the apertured and repeller electrodes in a direction transverse to the optic axis of the source, means for ionizing molecules of the beam in the source, means for applying a D.C. bias between the two repeller electrodes to counteract at least in part the ordered energy of the beam of material and so as to develop an ion beam generally along the optic axis of the source. The ordered energy of the ions resultant from the molecular sample beam results in a very poor focus of these ions on the optic axis in the absence of the referred to offset voltage on the repellers. This offset, or transverse component of propelling potential, counteracts this ordered energy and concentrates the ions on the optic axis. Simultaneously, ions of random energy are for the most part defocused relative to the optic axis and are thus excluded from the ion beam emergent from the ionizing region.

To further purify the analysis, and in its preferred

2

aspects, we impose an A.C. component on the D.C. propelling potential which sweeps this potential across the optimum potential offset for background ions, and accordingly the ion beam across the optimum focus on the outlet of the ionizing region. This causes the ions of ordered energy to produce a signal at the ion collector having a frequency component corresponding to that of the imposed A.C. signal, while ions of random energy which have a significantly different optimum offset potential will produce a signal at the collector having a frequency characteristic of twice this frequency. These collector signals are easily discriminated.

In preferred form the apparatus of the invention therefore includes means for superimposing an A.C. signal on the repeller electrodes to sweep the ion beam across the aperture in the apertured electrode. The invention also includes a mass spectrometer comprising an ion source as described above, means for separating ions emergent from the source in accordance with their specific mass, collecting means for selectively collecting ions so separated and, in preferred form, means for sensing collected ions discriminately as a function of the characteristic frequency of the ion current developed by the ions of interest at the collecting means.

The invention will be more clearly understood from the following detailed description thereof taken in conjunction with the accompanying drawing, in which:

Fig. 1 diagrammatically illustrates the difference in behavior of sample and background ions in the type of mass spectrometer under consideration;

Fig. 2 is a schematic illustration of a mass spectrometer in accordance with the invention;

Fig. 3 is a section taken on line 3—3 of Fig. 2; and Fig. 4 is a series of graphical notations illustrating

35 the operation of the mass spectrometer of Fig. 2.

Fig. 1 illustrates diagrammatically a response for a typical ion source on background ions and on sample ions. The ion yield of these two species in terms of ion current is plotted as a function of the repeller offset.

40 The "repeller offset" is a term applied to designate the difference in D.C. voltage applied to the two companion repeller electrodes. It will be observed from the curves in Fig. 1 that because of the ordered energy of the sample ions, a different repeller offset is required to achieve

45 peak ion current than is required for the background ions of generally random energy. A repeller offset of V_0 volts produces the most significant background signal, while an additional offset ΔV is required to develop the optimum sample signal. We have observed this fact and 50 utilized this observation to develop a mass spectrometer which, as previously pointed out, will selectively exclude from the electrical output of the instrument, ion currents resultant on the presence of background ionization.

The mass spectrometer shown schematically in Figs. 55 2 and 3 comprises in component form the usual ion source 10, analyzer region 11, and collector system 12 which, in practice, are all immersed in an evacuated envelope not shown in this drawing. The ion source 10 comprises a housing 13 having an aperture 13A in its forward wall for emergence of an ion beam 14.

The ion beam 14 enters the analyzer 11, which, in this instance, is represented schematically as a conventional 90° magnetic field, one pole 15 of the field forming magnet being shown. The magnetic field is of course established by a companion pole piece to the pole piece 15 and by suitable magnetic circuit between the pole pieces. Such means are conventional and form no part of the present invention. The segregated ion beam is discharged from the analyzer section through an apertured terminal electrode 16 for collection on a collector electrode 17 forming one element of the collection system 12.

The collector electrode is connected usually externally of the evacuated envelope to an amplifier 18 to amplify the collected ion currents and the amplifier in turn to a sensing means such as a recorder 19. For use with the present invention, the amplifier 18 is a tuned A.C. amplifier.

The ion source 10 is represented in this instance as provided with a crucible source of a molecular sample. A crucible 20 includes a cavity 21 for receiving a solid sample which, upon being sufficiently heated, emanates as a molecular beam which is collimated through an apertured plate 22 and an aperture 23 in a wall of the housing 13, the molecular beam passing transversely through the housing 13 through an outlet aperture 24 in the opposite wall of the housing to strike a catcher plate 25 for condensing un-ionized molecules.

An ionizing electron beam 27 is developed as shown in the section view of Fig. 3 in conventional fashion by a filament 28 energized by voltage source 29 and maintained at a negative potential with respect to the housing 13 by a bias battery 30. The filament is positioned to develop and direct the electron beam 27 through oppositely placed apertures, 31, 31A in the housing to strike target 32 which is maintained at a positive potential with respect to the housing by a bias battery 33. The molecular sample beam and the ionizing electron beam are preferably mutually perpendicular to each other and to the optic axis of the ion source, as represented by the ion beam 14, so as to intersect at a central point in the ion source resulting in concentrated ionization of the molecular beam at that point. A pair of repeller electrodes 36, 37 are connected to a D.C. voltage supply circuit 38, through a voltage divider network 39 to permit variation of the D.C. voltage levels of the two repellers. The housing 13 is maintained at a potential slightly negative with respect to both repellers to develop between the repellers and the outlet aperture of the housing a propelling potential to eject the ions from the housing.

An apertured electrode 42 is maintained at a negative potential with respect to the housing 13, in this instance ground potential, forming with the housing 13 an accelerating gap for propelling the ion beam 14 into the analyzer. An A.C. component of repeller differential is applied across the two electrodes 36, 37 through a transformer 44, the primary of which is connected to A.C. source 45. The adjustable tap 46 connected across this A.C. circuit enables adjustment of the difference in A.C. signal applied to the two repellers. Variation in D.C. offset is controlled through a bias network 48, adjustable tap 49 effecting this adjustment.

The operation of the instrument is in general similar to that of conventional sector-type mass spectrometers in that ions are formed within the ionizing region in the electron beam 27 at its point of intersection with the molecular sample beam. Under the influence of the potentials established between the repeller electrodes, the housing 13 and the accelerating electrode 42, the ion beam 14 is propelled from the ionizing region for separation in the analyzer 11. The separated ion components are then selectively focused on the collector 17 through the terminal electrode 16 for collection and sensing.

The A.C. component imposed on the repeller electrodes takes advantage of the unique characteristic of this type of instrument in distinguishing sample ions from background ions as a function of the fact that the repeller offset characteristics are different for the two types of ions. By imposing an A.C. voltage on the repellers and biasing this voltage so that, when the A.C. voltage is of zero amplitude, the background ion intensity is at a maximum, then with substantial A.C. amplitude at frequency ω the background ions will produce at the collector electrode frequency components of 2ω and higher, whereas the ion current signal from the sample molecules will have a

frequency ω and higher. For this reason by tuning the tuned amplifier 18 to frequency ω , the amplifier will be sensitive only to ions from the sample.

In Fig. 4, curve A illustrates the ion current from sample ions and curve B the ion current from background ions with a repeller offset as represented by curve C. The voltage designations V_0 and ΔV with respect to curve C are cross-referenced to the same designations in Fig. 1 illustrative of the different offset characteristics of the background and sample ions. It is observed from Fig. 4 that with the repeller offset varying at a frequency ω , the sample ion current is at the same frequency and the background ion current a frequency 2ω .

Any conventional means may be employed for sweeping the spectrum of the sample as for example simply changing the fields of the instrument. One typical technique involves variation of the accelerating voltage. In the illustrated circuit this can be accomplished by variations in the variable source 38 while maintaining a proportionate voltage offset between the propellers.

The invention is described with respect to a particular type of molecular source, i.e. a crucible source, and to a particular type of analyzer, although it is not so limited. The invention is useful as embodied with any ion source in which ions are formed with generally ordered rather than random energy so as to be distinguishable as a consequence from background ions. This may be a crucible source as shown, a source in which the sample is volatilized by a high vacuum spark, or a source using orifice-type inlet systems.

We claim:

1. A mass spectrometer ion source comprising an ionizing region, an apertured electrode disposed at one boundary of the region, first and second repeller electrodes disposed at the opposite boundary of the region, means for developing a molecular beam of ordered energy of material to be ionized means for directing the beam of molecules of ordered energy into the region between the apertured and repeller electrodes and transverse to the optic axis of the source, means for ionizing molecules in the beam of material within the region, means for applying a D.C. voltage offset between the two repellers to counteract at least in part the ordered energy of the ions formed in the beam of material and for focusing at least a part of said ions on the electrode aperture, means for varying the voltage offset between the repellers, means for superimposing an A.C. signal between the repeller electrodes to sweep the ion beam across the aperture, and means for varying the amplitude of the A.C. signal.

2. A mass spectrometer ion source comprising an ionizing region, an apertured electrode disposed at one boundary of the region, first and second repeller electrodes disposed at the opposite boundary of the region, means for developing a molecular beam of ordered energy of material to be ionized, means for directing the beam of molecules of ordered energy into the region between the apertured and repeller electrodes and transverse to the optic axis of the source, means for ionizing molecules in the beam of material within the region, means for applying a D.C. bias between the two repellers to counteract at least in part the ordered energy of the ions formed in the beam of material and for focusing at least a part of said ions on the electrode aperture, and means for superimposing an A.C. signal between the repeller electrodes to sweep the ion beam across the aperture.

3. In a mass spectrometer ion source comprising an ionizing region, an apertured electrode disposed at one boundary of the region, first and second repeller electrodes disposed at the opposite boundary of the region, means for directing a molecular beam of material to be ionized into the region between the apertured and repeller electrodes and transverse to the optic axis of the source, means for ionizing molecules in the beam of mate-

rial within the region, means for applying a D.C. bias between the two repellers to counteract at least in part the ordered energy of the ions formed in the beam of material and for focusing at least a part of said ions on the electrode aperture, means for superimposing an A.C. signal between the repeller electrodes to sweep the ion beam across the aperture, an analyzer section to separate ions of differing mass introduced thereinto from the ion source, collector means for collecting ions of a given mass, and a tuned A.C. amplifier tuned to the frequency of the A.C. signal.
